UNITED STATES PATENT OFFICE.

GEORGE G. FRELINGHUYSEN, OF MORRIS COUNTY, NEW JERSEY, ASSIGNOR TO STEEL UTILITIES, INCORPORATED, A CORPORATION OF NEW YORK.

LABEL FOR COMMODITY-PACKAGES.

1,289,431.

Specification of Letters Patent. Patented Dec. 31, 1918.

Original application filed October 11, 1916, Serial No. 125,120. Divided and this application filed February 15, 1918. Serial No. 217,332.

To all whom it may concern:

Be it known that I, GEORGE G. FRELINGHUYSEN, a citizen of the United States, and a resident of Morris county, in the State of New Jersey, have invented new and useful Improvements in Labels for Commodity-Packages, of which the following is a specification.

The invention relates to a novel dated commodity package label, which label has primarily three particular objects and advantages, although possessed of other features and advantages which will be indicated at a later point herein, or will be obvious herefrom, or may be learned by practice with the invention.

The three objects and advantages referred to above, are briefly:—

(a) The desirability of secret marking of a commodity package, decipherable only by the manufacturer or packager of the commodity, to indicate the date of making up or packaging the same. In the case of many commodities a dating of packages which is decipherable by the user or consumer will oftentimes create unfounded prejudice as to the condition of the contents, the user or consumer basing his judgment of the acceptability or fitness of the contents on the marked date rather than on a sampling of the contents of the package.

(b) The desirability of preserving the neat, pleasing, and artistic appearance of the label and general external appearance of commodity packages, as in many lines of merchandise great thought, labor, artistic ability and expense are bestowed on the making and affixing of labels to packages, as a means of enhancing the attractiveness and desirability thereof so as to increase sales and to build up the good will of the particular brand.

(c) The desirability of rapidly, easily and economically marking the labels themselves, and also the desirability of simplifying, facilitating and expediting the application of the labels to the commodity package, especially where this is done by machinery.

The present application is a division of my application Ser. No. 125,120 filed October 11, 1916.

The accompanying drawings are an exemplification of a particular label embody-

ing the invention, and of a machine which may be employed in dating such labels in the manner already explained, the labels being marked in gangs or packages.

Of the drawings:—

Figure 1 is an end elevation of a machine embodying the invention;

Fig. 2 is a section on the line A—B of Fig. 1; and

Figs. 3 and 4 illustrate labels.

It has been the practice to date labels by punching or perforating numerals throughout corresponding to the month, day and year, but this is objectionable because it causes adjacent labels to stick together and thus interferes with and stops the label affixing machine, causing a waste of both time and labels. Furthermore, so marking the labels is tedious and expensive, as the labels can be punched only in small groups or bunches, and the punches are rapidly dulled and must be frequently replaced. With certain lines of merchandise such universally decipherable dating by perforating the numerals of the day of month and year in the label is objectionable, as consumers are thereby frequently groundlessly prejudiced against commodities.

By means of the present invention, the labels may be marked in packs or bundles of thousands, the marking of a group of one or more thousands of labels consuming very little labor, and sufficient labels for the daily output of even the largest factories may thus be chronologically marked in a very brief time. Further by this invention the marking of the labels does not cause them to stick together, also there is but little wear on the marking mechanism, and when desired the mark may be undecipherable by the consumer.

Referring to the accompanying drawings, illustrating by way of example an embodiment of the invention, the labels *x* which may number hundreds or thousands, are firmly clamped together in a carrier, and when so clamped their edges are indented at selected places or points corresponding to months and days of the month. As shown, the labels *x* are of irregular conformation although rectangular or circular or other shaped labels may be employed if desired. The label holder comprises end

plates 1 and 2, to one of which is attached a side and bottom support 3. The other end plate is shaped to pass within the support 3, so that groups of labels varying widely in number may be held in the carrier and marked.

The plates 1 and 2 of the carrier are movable from each other to receive the labels α and are movable toward each other to firmly 10 press together and hold the labels for marking. In the embodied form, the end plates 1 and 2 are provided, respectively, with internally screw-threaded bosses 4 and 5, which bosses are in threaded engagement 15 with a right-hand and left-hand screw-threaded shaft 6. When the shaft 6 is turned in one direction, the plates 1 and 2 recede from each other and when the shaft 6 is turned in the other direction, plates 1 20 and 2 approach each other and press together and firmly hold the labels α . The end plates 1 and 2 have at their bottoms projections 7 and 8, which enter into and travel along a groove 9 in a bed plate 10 of the 25 machine. The shaft 6 is conveniently provided with a handwheel 11 for turning it in either direction. The shaft 6 is rotatably journaled in bearings 12 and 13 formed on the machine frame, and is longitudinally 30 slidable or reciprocable in its bearings to feed the labels past the marking device.

The embodied form of marking device comprises a rotating miller or saw 14, mounted on a shaft 15 of a motor 16, the 35 saw 14 being preferably within a safety casting 17.

Means are provided for relatively positioning the marking device 14 and the gang or labels α in accordance with the day and 40 month to be marked on the label. In the embodied form of such means, the motor 16 is slidable (to the right and left in Fig. 1) upon a table 18, which table is carried upon a bracket 19 fixed to the machine frame. 45 The base 20 of the motor is formed to slide upon the table 18 and has a portion projecting into a grooved guideway 21 in the face of the table 18. Projecting downwardly from the base 20 is an internally screw-threaded lug 50 22. The lug 22 is in threaded engagement with a screw shaft 23, which shaft is journaled in supports 24 and 25 formed on the underside of the table 18. The screw shaft 23 may be provided with a handle 26.

55 Chronological indications are provided for indicating the position of the marking device 14 relatively to the labels in the holder. With the form of label shown, it is convenient to indicate the dates by secret markings at the edges a , b , c , and d of the labels. Thus anyone of four points or positions along edge a may be selected for notching and may be used for the first four months of the year. Four similar points or positions at the edge b may be used and may be

selected for the succeeding four months of the year, and four points or positions at the edge c may be used, and selected when needed, for the remaining four months of the year. A notch selectively placed at any one 70 of these positions would indicate the month of the year in which the commodity was packaged. At the edge d , would be four positions indicating the weeks of the month, thus two notches selectively placed in the 75 edge of the label, one notch at the proper point in either of edges a , b or c , and the other notch at the proper point in edge d , would give the date of packaging within a limit of one week. It will be obvious that 80 the arrangement of notches may be varied as desired to indicate the precise day of the month, and also to indicate the year of packaging in like manner where this might be desirable.

85 If it is desired to keep the date secret from the consumer, there need be no typographical or other indications upon the label which would be ordinarily decipherable, while on the other hand if this should not be 90 an object, numerals could be placed upon the label whereby the date could be read. It will usually be found sufficient for the secret or arbitrary markings to bear a definite predetermined relation to the edges, or otherwise to the contour of the label, or to the lettering or other markings on the label used to describe or decorate the package or otherwise. If desired, a master plate or index 95 may be utilized by the manufacturer to read 100 the secret marking of the labels, but usually in practice the labels can be read by the eye of one familiar therewith and knowing the system of secret marking.

105 In the embodied form, as stated, the relative change of position between the marking device and the clamped labels for indicating the date is effected by moving the motor and marking device to the right and to the left in Fig. 1. The chronological index in the present case comprises four marks 27 on the table 18, and a co-operating mark 28 on the base 20 of the motor 16. The four marks on the table correspond to the points or positions on the edges of the label for days, 115 weeks or months, and the mark 28 corresponds to the selected date which will be marked by the marking device. The marking device 14 may be accurately positioned by turning the handle 26 of the screw shaft. 120

125 The shaft 6 is drawn forward or back so that the labels clamped in the carrier may be clear of the marking device, say to the right in Fig. 2 as the shaft is slidable in its bearings 12 and 13. Shaft 6 is rotated to move plates 1 and 2 away from each other so that the gang or package of labels α may be placed within the carrier. Shaft 6 is then rotated in the opposite direction to press plates 1 and 2 together and so firmly hold 130

the gang of labels α . The motor 16 is started, and the shaft 6 is moved longitudinally, sliding in its bearings 12 and 13, and carrying the plates 4 and 5 with the gang of 5 labels, to feed the labels past the marker 14, thereby marking them at the selected chronological point.

The labels can be applied to the package by any suitable or approved packaging or 10 label affixing machine, and these machines or their manner of operation need not be described in detail herein.

What I claim is:—

1. A commodity label having a mark 15 thereon located with respect to the label to indicate the date of packaging of the commodity.
2. A commodity label having a notch in the edge thereof located with respect to the 20 label to indicate the date of packaging of the commodity.
3. A commodity label having a plurality of marks thereon so located with respect to the label as together to indicate the date of 25 packaging of the commodity.
4. A commodity label having a plurality

of marks thereon arbitrarily located with respect to the label so as together to indicate the date of packaging of the commodity.

5. A commodity label having a plurality 30 of marks in the edge thereof so located with respect to the label that together they indicate the date of the packaging of the commodity.

6. A commodity label having a plurality 35 of marks thereon so located with respect to the label with reference to the lettering or other markings on the label as together to indicate the date of packaging of the commodity. 40

7. A commodity label having a mark thereon so located with reference to the lettering or other markings on the label as to indicate the date of packaging of the commodity. 45

In testimony whereof, I have signed my name to this specification, in the presence of two subscribing witnesses.

GEORGE G. FRELINGHUYSEN.
